ABSTRACT

A facsimile recorder marks a paper impregnated with electrolyte and a lake former by migration of ions from an endless loop metal electrode to the paper when electrical current is passed from the electrode to a cooperative electrode through the recording paper pressed therebetween. The loop electrode is fed through a track which holds a portion of it straight where it opposes the cooperative electrode, and has a coating of fine molybdenum-containing material bonded to its surface to prevent the accumulation and adhesion of lake on the loop electrode which would impede free feed of the loop electrode through the track.

ATTORNEY

FACSIMILE RECORDER AND MOVING ELECTRODE THEREFOR

BACKGROUND OF THE INVENTION

One widely used electrolytic facsimile recorder comprises an elongate metallic blade electrode pressing on one side of a moving sheet of moist paper impregnated with electrolyte and a lake former. Pressing on the opposite side of the paper is a second electrode helically curved around a rotating drum such that the pressure point against the blade electrode sweeps along the blade once each revolution of the drum. Simultaneously electrical signal current is passed from the blade to the helix causing migration of metal ions from one edge of the blade to the paper and formation of a colored lake with the paper impregnant. Migration of metal ions from a stationary blade unevenly erodes the blade and results in uneven density of lake forming across the paper. Therefor it is highly desirable to feed the blades slowly and continuously lengthwise to prevent uneven erosion. Preferably the blade electrode is in the form of an endless loop guided in tracks on a straight path where it opposes the helical electrode.

However, the colored lake formed at the edge of the loop pressing on the paper accumulates on the blade during recording and adheres to the blade to the extent that it jams in the guide tracks subjecting the blade to uneven erosion.

The object of the present invention is to prevent the accumulation and adhesion of lake on the blade electrode.

SUMMARY OF THE INVENTION

According to the invention facsimile apparatus for recording on electrolyte and lake former impregnated paper comprises an endless loop electrode of flexible metal, guide means engaging the loop electrode to hold a portion thereof on a linear path, means to feed the loop electrode through the linear path, a second electrode opposed to the linear portion of the loop electrode cooperating with the loop electrode when electrical current is passed between the electrodes through the paper to mark signals on electrosensitive paper pressed between the two electrodes by migration of metal ions from the loop electrode to form a lake with the electrolytic impregnation on the paper and on the edge of the loop electrode pressing against the paper, said loop electrode having a coating containing molybdenum bonded to the surface of the electrode for preventing the accumulation and adhesion of said lake to the loop electrode and allowing continued feed of the loop electrode through the guide means.

DRAWINGS

For the purpose of illustration a typical embodiment of the invention is shown in the accompanying drawing in which:

FIG. 1 is an isometric view of an endless loop electrode facsimile recorder; and

FIG. 2 is an enlarged section on line 2-2 of FIG. 1.

DESCRIPTION

Shown in FIG. 1 is a facsimile recorder for marking a web P of moist paper impregnated with an electrolyte, a lake former and a sequestering agent such as are dis-

closed in U.S. Pat. No. 3,409,516. The paper is slowly fed between a loop electrode 1 and a helical electrode 2 secured around a drum 3. The drum is rotated at several hundred revolutions per minute by a motor M1 so that the point of the electrode 2 pressing toward the opposed straight portion of the loop electrode scans along the straight portion in synchronism with the application of facsimile signals from a source 4 to the loop and helical electrodes. The loop electrode is formed of a thin flexible blade or strip of stainless steel or like ion forming metal, and when in contact with the electrolyte of the paper its lower, recording edge 6 releases iron ions which then combine with the lake former in the paper to form a colored lake. Most of the lake is retained in the paper, but after several hours of operation an accumulation of lake, paper fibers and other electrolytic recording by-products builds up at and above the recording edge of the blade electrode.

The endless loop electrode 1 is inserted in a guide track formed by the flange 5 of a mounting plate 7 and an opposed guide rail 8 secured to the flange 5. Opposite the helical electrode 2 the loop electrode is held straight and rather snugly by the guide track along the effective recording portion of the loop. At both ends the guide rail 8 curves around the path of the loop electrode, the left end being broken away to show two sprocket wheels 9 and 11 coupled by a sprocket chain. The smaller wheel 9 is driven by a low speed motor M2. The larger wheel 11 has teeth 13 engaging in sprocket holes 14 in the loop and driving the loop through the guide track at a barely perceptible speed. It is between the guides 5 and 8 that an accumulation and adhesion of lake and other recording by-products on the loop electrode, or scraped from the loop electrode, causes jamming and arrest of the loop electrode.

To avoid such accumulation or adhesion on the loop electrode a thin film of finely divided molybdenum, e.g. disulfide, particles is bonded to the surface of the loop electrode by a thermosetting, ceramic bonding agent. An example of such is available under the trademark Electrofilm 4396 from Electrofilm Inc., 7116 Laurel Canyon Blvd., North Hollywood, California. This film is conventionally used as a solid lubricant to reduce metal to metal friction rather than as an antiadhesion agent for preventing the accumulation and adhesion of lakes and other electrolytic recording by-products such as paper fibers, and has a composition by weight of approximately 90 percent molybdenum disulfide and 10 percent graphite in a thermosetting resin modified with an elasticizer. Other conventional lubricants do not have the antiadhesion property of this molybdenum film. Moreover, if the molybdenum film is applied to the guide track in its usual use as a lubricant, the sprocket holes 14 of the loop electrode 1 chew it off and destroy its lubricating effect.

The loop electrode is first degreased and then sand blasted or otherwise etched. The mixture of molybdenum and bonding agent in a suitable solvent is dip coated or sprayed on the loop to a thickness of 0.00025 to 0.005 of an inch, and cured by thermosetting at 375° F for one and one half hours.

It has been found that such a coating on the loop electrode substantially reduces adhesion of lake and recording by-products on the loop electrode despite the expected accumulation. In over eighty hours of

operation, equivalent to several weeks of normal daily recording use of such a blade, jamming in the guide track was completely eliminated.

It should be understood that the present disclosure is for the purpose of illustration only and that this invention includes all modifications and equivalents falling within the scope of the appended claims.

I claim:

1. Facsimile apparatus for recording on electrolyte and lake former impregnated paper comprising: an elongate stripe electrode of flexible metal, guide means engaging the loop electrode to hold a portion thereof on a linear path, means to feed the loop electrode lengthwise through the guides means on the linear path, a second electrode opposed to the linear portion of the loop electrode cooperating with the loop electrode when electrical current is passed between the electrodes through the paper to mark signals on electrosensitive paper pressed between the two electrodes by migration of metal ions from the loop electrode to form a lake with the electrolytic impregnation on the paper and on the edge of the loop electrode pressing against the paper,

said loop electrode having a coating containing a solid lubricant molybdenum compound of the group characterized by having antiadhesive properties bonded to the surface of the electrode for preventing the accumulation and adhesion of said lake on the loop electrode and allowing continued feed of the loop electrode through the guide means.

2. A moving electrode for electrolytic formation of a lake on an electrolyte and lake former impregnated recording web across which the electrode is fed through a guide track, comprising an elongate strip of flexible metal capable of electrolytic release of metal ions to form a lake on the paper at one edge of the electrode, said strip having a thin coating containing in its place bonded to the surface of the electrode inhibiting the accumulation and adhesion of the lake on the electrode whereby to allow free continued feed of the electrode through the guide track.

3. A moving electrode according to claim 2 wherein said metal is stainless steel.

4. A moving electrode according to claim 2 wherein said coating contains molybdenum disulfide.
